UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

CHANNELER.

Application filed July 12, 1922. Serial No. 574,406.

My invention relates to channelers and more particularly to improved controlling mechanism for employment with channelers.

An object of my invention is to provide an improved channeler mechanism. Another object of my invention is to provide an improved channeler mechanism having improved means for controlling the cushioning thereof. A further object of my invention is to provide an improved channeling mechanism in which overheating is prevented. A still further object of my invention is to provide an improved channeling mechanism having an improved adjustable control mechanism for varying the cushioning and the supply of air to the operating mechanism of the channeler to prevent overheating of the same. Other objects and advantages of my invention will hereinafter more fully appear.

In the accompanying drawings I have shown for purposes of illustration one form which my invention may assume in practice.

In these drawings,—
25 Fig. 1 is a detail vertical section, partially in elevation, through a channeler chopping engine provided with my improved mechanism.

Fig. 2 is a detail section on the line 2—2
30 of Fig. 1.

Fig. 3 is a transverse section on the line
3—3 of Fig. 2.

Fig. 4 shows both a plan view and a side elevation of the spring constituting a part
35 of my improved mechanism.

As the parts with which my improvement in channeling mechanisms is incorporated are in general old, it will be sufficient to describe them simply. It will be observed that
40 a crank shaft 1, which may be mounted in any suitable manner upon a standard and driven by a usual motor not shown, is connected by a pair of connecting rods 2 to trunnions 3 arranged at opposite sides of
45 the lower head 4 of a cylinder 5. The cylinder 5 contains a piston 6 having a piston rod 7 and tail rod 8 which are guided in the opposite ends of the cylinder. The piston rod 7 carries at its lower end a gang of
50 channeling tools 9 supported in a suitable cross head 10. As in a well known construction, the cylinder comprises a lower head 4 and an upper head 12 between which a relatively light cylinder body 13 is arranged,
55 the heads being connected by a plurality

of tie rods 14 of which three are visible. The upper cylinder head 12 is provided with a tubular extension 15 containing a split bushing 16 in which is guided the tail rod 8, and as the latter is not a tight fit for its opening 8' in the head 12, air may pass from the cylinder into the extension 15. The upper end of the extension 15 preferably terminates in a tubular cap 17 having a perforated end 17' through which air may be discharged from the upper end of the cylinder. The wall of the cylinder 13 is traversed between its ends by a pair of longitudinally spaced ports 18 and 19 connected by a longitudinally extending bypass passage 20. The lower cylinder head 4 is provided with one or more inlet ports 21 opening into the interior of the cylinder and a suitable check valve 22 opening toward the interior of the cylinder, carried in suitable guides 22' and normally held seated by a spring 23 and controlled as to its degree of opening by a stop 24, controls the admission of air through the passages 21. The cylinder wall is also perforated between the ends thereof as at 25 by a combined lubricant and breathing port. When the valve 22 is open and the piston in mid position, there is a passage open from end to end through the cylinder and cap 17, and during channeling there is a gradual pumping of air through the cylinder and cap which serves as a cooling medium and thereby tends to keep down the temperature of the relatively movable parts.

As in practice it is often necessary to change the quantity of air which may be admitted through the ports 21 to the lower side of the piston 6, for the purpose of varying the degree of cushioning, I have provided a suitable mechanism for the purpose of permitting a large or small quantity of air to have access to the valve 22 and so to the interior of the cylinder. The valve 22 cooperates with a seat 26 which is carried in a member 27 threadedly connected to the lower cylinder head 4. Below the valve seat 26 is arranged a recess 28 which is coaxial with the valve seat and which contains a pair of ported plates 29 and 30, a stiff spring 31 and a follower 32 threaded into the lower extremity of the recess. The plates 29 and 30 are each round and are traversed by series of ports 33, these ports in the plates 29 and 30 being so spaced that it will be

possible for the ports to be moved out of register with each other by arranging the plate 30 in a manner to be described with the ports thereof out of alignment with the 5 ports in the plate 29. A suitable pin 34 holds the ported plate 29 against rotation. The plate 30 is provided with a slot 35 which permits the turning of the plate between certain limits, the limits of turning being such as to 10 permit the ports 33 in the two plates to be brought into full register or to be brought entirely out of register with each other. The plates may be provided with mating serrations 37 and the lower plate 30 may also 15 have notches 39 therein with which projecting portions 38 formed upon the spring member 31 are adapted to engage. It will be clear that if the spring is held against rotation, as may be done by notching it to 20 receive the pin 34, the spring may serve as further locking means for the plate 30, while, if desired, the spring need not be fixed and simply by maintaining the serrations 37 interlocked with each other any 25 tendency to relative rotation between the plates will be avoided. It will also be evident that, if desired, the serrations 37 may be omitted entirely and reliance placed upon the friction between the plates. The plate 30 is provided with a central depending boss 30 or shank 40 upon which a wrench may be fitted for the purpose of turning the plate to bring the holes 33 in the plate 30 more or less into full communication with those 35 in the plate 29. As shown, the plates are slightly spaced so as to prevent total interruption of air admission, but this may be accomplished in other ways or wholly omitted under certain conditions if desired. 40 The mode of operation of my illustrative embodiment described herein will be readily apparent. It will be evident that, as the cylinder 5 is reciprocated upon rotation of the crank shaft 1, the piston 6 will be thrown 45 by the alternate compressions and releases of the air at opposite sides of the piston 6 as the cylinder reverses its direction of travel. It will be evident that there will be some leakage of air and that there will 50 also be some air discharged through the port 25 formed in the side of the cylinder for the admission of lubricant thereto. The degree of cushioning will also be regulated by the quantity of air that is admitted beneath 55 the piston at each upward stroke. Accordingly, in very soft stone it may be necessary to use more than one of my improved controlling mechanisms to provide adequate inlet capacity, while in very hard rock it 60 will be possible to entirely close all except one of these mechanisms and to largely close off communication through the ports 33 in that one of them. In any event, it will be observed that by the employment of one or 65 more of my improved regulating mecha-

nisms, it will be possible to determine precisely the quantity of air which will be admitted into the lower end of the cylinder and so to vary the degree of cushioning with great nicety to suit any condition of channelling. It will be obvious that I am not limited to the form of spring which I have illustrated at 31 in Figures 2 and 4, but that any other form, for instance an annular bowed spring, a corrugated spring, or other 75 constructions may be employed if desired.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure 85 by Letters Patent is:

1. In a stone working machine, in combination, a cutting tool, actuating means therefor including a reciprocable cylinder having a piston movable therein, said cylinder having fluid inlet means including a port, fluid outlet means, and passage means for conducting fluid to the opposite ends of said cylinder, an automatic valve for controlling fluid flow to said inlet port, and means 90 for regulating fluid flow to said automatic valve.

2. In a stone working machine, in combination, a cutting tool, actuating means therefor including a reciprocable cylinder having a piston movable therein, said cylinder having an inlet opening and an outlet opening, and a by-pass extending to opposite ends of said cylinder for conducting fluid from the inlet opening to said opposite ends, an automatic valve for controlling fluid flow through said inlet opening, and means for regulating the flow of fluid to said automatic valve.

3. In a stone working machine, in combination, a cutting tool, a power driven member, and means for transmitting power from said power driven member to said cutting tool including a cylinder, a relatively movable piston therein, and means for causing a substantially one-way flow of air through said cylinder comprising a port at each end of said cylinder and arranged to be in communication at least during a part of the relative movement between said cylinder and piston in either direction, an inwardly opening check valve controlling one of said ports, and means for regulating the rate of fluid flow to said check valve.

4. In a stone working machine, in combination, a cutting tool, actuating means therefor including a reciprocable cylinder having a piston movable therein, said cylinder having a fluid inlet opening and a fluid outlet opening, and a by-pass connecting the opposite ends of said cylinder, an automatic valve 125

for controlling fluid flow through said inlet opening to said cylinder, said valve being automatically closed on relative movement of said piston and cylinder in one direction, and means for regulating the flow of fluid to said automatic valve.

5. In a stone working machine, in combination, a cutting tool, actuating means therefor comprising a reciprocable cylinder and a piston movable therein, said cylinder having a fluid inlet opening in the lower end thereof, and means for varying the quantity of air flowing through said opening thereby to vary the resistance to relative movement between said cylinder and piston.

6. In a stone working machine, in combination, a cutting tool, actuating means therefor including a reciprocable cylinder having a piston movable therein, said cylinder having an inlet opening and an outlet opening in the opposite ends thereof respectively, means for intermittently connecting said openings, a check valve controlling fluid flow through one of said openings, and a manually adjustable throttle valve controlling the flow of fluid to said check valve whereby a maximum blow struck by said tool occurs only during a minimum fluid cushion.

7. In a stone working machine, in combination, a cutting tool, actuating means therefor comprising a cylinder, means for reciprocating the same, and a piston movable in and relative to said cylinder and rigidly connected to said cutting tool; means for supplying air to both ends of said cylinder, and means for controlling said supply means to vary the resistance to relative movement between said cylinder and piston in both directions.

8. In a stone working machine, in combination, a cutting tool, actuating means therefor comprising a cylinder, means for

reciprocating the same, and a piston movable in and relative to said cylinder and rigidly connected to said cutting tool; inlet means for automatically supplying air to said cylinder on opposite sides of said piston, restricted outlet means for relieving pressure on both sides of said piston, and means for controlling the amount of air to said inlet means for varying the maximum pressures in said cylinder on both sides of said piston.

9. In a stone working machine, in combination, a cutting tool, actuating means therefor comprising a cylinder, means for reciprocating the same, and a piston movable in and relative to said cylinder and rigidly connected to said cutting tool; inlet means for admitting air to one end of said cylinder, means for conducting air from said end to the opposite end of the cylinder, exhaust means at said opposite end, and means for regulating the amount of air supplied to said inlet means to vary the resistance to relative movement between said cylinder and piston.

10. In a stone working machine, in combination, a cutting tool, actuating means therefor comprising a cylinder, means for reciprocating the same, and a piston movable in and relative to said cylinder and rigidly connected to said cutting tool; an inlet opening for admitting air to one end of said cylinder, an automatic valve in said opening, a restricted passage connecting the opposite ends of said cylinder, a restricted exhaust port communicating with the end of said cylinder opposite said inlet opening, and a valve for regulating the amount of air supplied to said inlet means to vary the resistance to relative movement between said cylinder and piston.

In testimony whereof I affix my signature.

HENRY H. MERCER.
